Fig. 3.

Diagram illustrating a motor control circuit. The motor has a shunt field and a series field. The shunt field is connected to a power source and a 'SLOW DOWN LIMIT SWITCH' (T17). The series field is connected to a power source and an 'ARM' switch (T15). A 'STALL LIMIT SWITCH' (T16) is connected in series with the shunt field branch. The motor armature is connected to a power source and a 'T' switch (T1). The circuit also includes a 'T3' switch and a 'T4' switch. A large rectangular component is labeled 'T1'.

OF CHICAGO, ILLINOIS, A CORPORATION OF MAINE

HYDRAULIC ELECTRIC BELL HOIST

Application filed June 2, 1927. Serial No. 195,882.

The present invention relates to hydraulic electric bell hoists. More particularly the present invention relates to structure suitable for operating the loading bells of blast furnaces. In order to cut down the labor in loading blast furnaces it is highly desirable to control the operation of a blast furnace bell automatically, whereby upon the movement of a simple switch, valve or the like, a cycle is inaugurated and carried through, resulting in the desired operation of the blast furnace bell. This cycle may be inaugurated in response to the operation of the skip hoist or other device for loading the bell. In a blast furnace plant, the skip hoist, involving the distributor and the bells, may be interlocked, so that it is necessary for the scale car operator only to start the skip hoist in order to bring about a complete cycle of operation comprising the movements of the skip hoist, distributor and bells.

An object of the present invention is to provide a bell hoist which involves relatively simple parts, which is positive in operation, which requires a minimum of space, which provides the necessary speed control and which will cut down to a minimum the amount of attention required of an operator. A further object is to provide a bell hoist involving a combination of hydraulic and electrical mechanisms which is well adapted to meet the needs of commercial operation.

A further object is to provide a system involving separate operating mechanisms for the two bells of a double bell blast furnace, either of which operating mechanisms may be conveniently used for operating either of said bells.

Further objects will appear as the description proceeds.

Referring to the drawings—

Figure 1 is a diagrammatic view illustrating one embodiment of the present invention;

Figure 2 is a diagrammatic view illustrating an electrical layout which may be used in the practice of the present invention; and

Figure 3 is an electrical circuit illustrating certain details of the circuit shown in Figure 2.

The present invention contemplates a novel combination of counterweighted hydraulic cylinders connected directly with the cables leading to the bell levers of a blast furnace. It is the function of each hydraulic cylinder to hoist its corresponding counterweight, thereby permitting the corresponding bell to open by gravity. It is a further function of the hydraulic cylinder as contemplated in this invention to provide a retarding motion during the lowering of the counterweight, whereby to govern the speed of the closure of the corresponding bell. In connection with each hydraulic cylinder, it is proposed to use a rotary hydraulic pump, of which there are several types available in commercial use. The particular types of hydraulic pumps contemplated are such that they can be used interchangeably for pumping fluid under pressure or as hydraulic motors to convert hydraulic pressure to rotary motion. The pump referred to is connected to a dynamo-electric machine, which operates as a motor or as a generator, depending upon whether said dynamo-electric machine is called upon to perform motor or generator functions. Not only does the hydraulic system function to translate straight line movement to rotary movement, and conversely, but it also functions to translate from high speed motion of the motor with a small torque to a low speed motion of the hydraulic cylinder with large force, or, conversely, from a low speed motion of the hydraulic cylinder with a large force to a relatively high speed motion of the motor with generator functions. In this action the present invention contemplates the replacement of gear reducing means or arrangements of cables and sheaves. If the cable pull of the bell hoist is applied directly to any form of winch mechanism, said mechanism must be heavy enough in construction to handle the large forces corresponding to the cable pull. If, on the other hand, it is desired to construct a small winch or other mechanism to handle the bells or counterweights, it is necessary to interpose a considerable number of sheaves and cables in order to translate the large force with slow motion of the bell cables to the smaller force with faster motion at the winch.

The cycle of operation of the hoisting mechanism for each bell may be substantially the same as described in applicant's copending application Serial No. 97,811, filed March 5 26, 1926, entitled Electric hoists. According to the present invention, in order to open the bell the electric motor is started, driving a hydraulic pump and causing a flow of fluid into a cylinder and raising a counterweight 10 and allowing the bell to open. When the bell has opened a desired amount, the motor can be made, by means such as described in said application and which will be described hereinafter, to slow down and substantially stop, 15 as for example by introducing suitable resistors in series and in shunt with the motor. After a desired period, or upon the happening of a certain event, the electrical circuits can be changed to allow the counterweight 20 to lower. In so doing, the counterweight will force fluid out of the cylinder and through the rotary pump into a storage reservoir. In so doing, the pump will drive the motor in the reverse direction as a generator. By the 25 provision of suitable braking circuits, which braking circuits will be referred to hereinafter, the retarding effect of the motor may be regulated to thereby govern the speed at which the counterweight is lowered. Moreover, the present invention contemplates means whereby the cycle may be interrupted as desired and the bell and counterweight may be held in an intermediate position or an open position.

30 Referring to the drawings, the letter A represents one bell and the letter B indicates a second and larger bell, which cooperate with one another in the loading of the blast furnace C. The two bells A and B may be arranged concentrically in a manner which is common in practice, the bell A being controlled by a cable D, while the larger bell B is controlled by the cable E, levers F and G being connected to said cables D and E, respectively, said levers F and G being connected to the bells A and B, respectively. The cable D is connected to the hydraulic cylinder H, which is adapted to have a reciprocating movement along a vertical axis, the 35 inner wall of said cylinder H having fluid-tight sliding engagement with the fluid supply member I, the interior of which is connected by means of the pipe J to rotary fluid pumps and liquid reservoirs, to be referred to hereinafter, the pipe J being provided with the valve J¹. The cable E is connected to the cylinder K, which is adapted to have a reciprocating movement along a vertical axis, the inner wall of said cylinder K having 40 sliding fluid-tight engagement with the fluid supply member L, the interior of which is connected by means of the pipe M to the two rotary pumps and fluid reservoirs above referred to, the pipe M being provided with the valve M¹. Each of the cylinders H and K

is provided with a counterweight N, which may be chosen of a size suitable for the bell with which it cooperates.

As noted from Figure 1 of the drawing, the pipes J and M are connected to the common pipe O, which common pipe is connected to the corresponding sides of the rotary pumps P and Q through the pipes P¹ and Q¹. The pipe O is provided with the valve O¹ between the pipes J and M. The other sides of said rotary pumps P and Q are connected to the oil reservoirs R and S through the pipes P² and Q². Pipes P¹ and Q¹ are provided with the valves P³ and Q³, respectively. The pipes P¹ and Q¹ are also connected to the upper regions of the reservoirs R and S through the relief pipes R¹ and S¹, respectively, which relief pipes R¹ and S¹ are provided with the relief valves R² and S². Connected to drive the rotary pump P is the dynamo-electric machine T, and similarly connected to drive the rotary pump Q is the dynamo-electric machine U. The control panels for the dynamo-electric machines T and U, respectively, are indicated by the characters T¹ and U¹. Connected to the control panel T¹ are the stall limit switch T² and the slow-down limit switch T³. Said stall limit switch T² is adapted to be closed by a portion of the cylinder H, or a member which moves with said cylinder H when said cylinder H is at or near the upper limit of its travel, and the slow-down limit switch T³ is similarly adapted to be opened when said cylinder H is a short distance above the lower limit of its travel. Abutments H¹ carried by said cylinder H are illustrated, for controlling the switches T² and T³. Similarly connected to the control panel U¹ are the stall limit switch U² and the slow-down limit switch U³ which are adapted to be selectively operated by the cylinder K when said cylinder is at predetermined places in its range of travel. Abutments K¹—K¹ carried by the cylinder K are illustrated, for controlling the switches U² and U³. Panel T¹ is connected to switch T² by means of the two-wire cable T⁴ and to switch T³ by the two-wire cable T⁵. Similarly, panel U¹ is connected to switch U² and to switch U³ by means of the two-wire cables U⁴ and U⁵, respectively. Panels T¹ and U¹ are connected to the dynamo-electric machines T and U by the four-wire cables T⁶ and U⁶, respectively. Each of the cables T⁴ and U⁴ is provided with a switch X.

An electric control system for each of the dynamo-electric machines is illustrated in Figure 2, said system being part of the subject matter of another application filed by the present applicant and is therefore not being claimed herein. Said other application bears Serial No. 97,811, and was filed March 26, 1926.

The armature of either dynamo-electric

machine T or U is indicated in Figure 3 by the numeral 15, and the series field winding and the shunt field winding of said dynamo-electric machine are indicated by the numerals 16 and 17, respectively. The numerals 18—18 indicate the two leads of an electric circuit which may be controlled by the blades 19—19 of a double-pole switch.

Connected across the leads 18—18 is a circuit including contactor 20, the armature 15, the series field winding 16, the sections 21, 22 and 23 of an accelerating resistance, and the contactor 24. Also connected in the circuit referred to is the overload relay coil 25. The sections 21, 22 and 23 of the accelerating resistance are adapted to be shunted out of circuit for which purpose accelerating contactors 27, 28 and 29 are provided. Connected in parallel across the circuit of the armature 15, series field winding 16 and section 21 of the accelerating resistance is a shunting circuit controlled by the normally closed contactor 30. The normally closed spring contactor 31 is provided for connecting the braking resistors 32 across the circuit including armature 15, series field winding 16 and sections 21 and 22 of the accelerating resistance.

Connected across the leads 18—18 is a circuit including the normally closed time delay relay 33, the operating coils 34 and 35 (which coils are in parallel with each other) and the normally open start button 37. The normally closed overload relays 38—38 may be provided in the circuit immediately above described, which overload relays 38—38 are responsive to energization of the overload relay coil 25. Connected in parallel relationship with the time delay relay 33 and the coils 34 and 35 is the operating coil 39 for contactor 30. Operation of the start button 37 connects said operating coil 39 across the leads 18—18. Arranged in parallel relationship with the start button 37 is the slow-down limit switch T³, which is biased to closed position. Connected in parallel relationship with the start button 37 and the slow-down limit switch T³ is the auxiliary contact 41, which moves in unison with contactor 20. Said auxiliary contactor 41 is in closed position when contactor 20 is in closed position.

Mounted in parallel relationship with the operating coil 39 for the contactor 30 is a circuit including the stalling limit switch T², the operating coil 43 for the contactor 31, and an auxiliary contact 44, which is mounted to move in unison with contactor 20. Said auxiliary contact 44 is in closed circuit position when contactor 20 is in closed position. Connected across the operating coil 43 is the operating coil 45 for the accelerating relay contacts 46, 47 and 48, which control the relay coils 46^a, 47^a and 48^a, respectively, which coils in turn control contactors 27, 28 and 29, respectively.

Also connected in parallel circuit across

the operating coil 39 for the contactor 30 is the operating coil 49 for the time delay relay 33 and the auxiliary contact 50, which moves in unison with the contactor 31. Said auxiliary contact 50 is closed when contactor 31 is closed.

Figure 3 indicates the connections of the slow-down limit switch and the stall limit switch with the panel T¹ and the connections of the dynamo-electric machine T with said panel. It will be understood, of course, that the connections of the panel U¹ with its corresponding slow-down limit switch and stall limit switch and with its corresponding dynamo-electric machine U will be similar to those shown in Figure 3. In Figure 1 the numeral 51 indicates a connection between the panels U¹ and T¹ by means of which either panel may be used with either of the dynamo-electric machines. This connection forms no part of the present invention and need not be described herein.

The bells A and B are normally held in sealed position by the pull of the cylinders H and K, respectively, which cylinders act as counterweights. In charging the furnace C it is necessary to communicate lifting movements to said cylinders H and K. Inasmuch as the operations of said cylinders are normally independent of one another, a description of the control of one of said cylinders will suffice for a description of the control for the other of said cylinders. Referring for example to the cylinder H, which controls the upper bell A, it is necessary, in order to raise same, to set the corresponding dynamo-electric machine T in operation as a motor. Operation of the dynamo-electric machine T as a motor drives the pump P, causing a flow of oil or other fluid from the reservoir R through said pump P and pipe line J to the fluid supply member I. Flow of oil through the member I to the cylinder H results in the lifting of the cylinder H, allowing the bell A with its burden to open. When the bell has opened a desired amount, the motor can be made to slow down and substantially stop by introducing suitable resistors in series and in shunt with the motor. After a desired period, as determined by a time relay, or upon the happening of a certain event, the electrical circuits can be changed in a manner whereby the counterweight comprising the cylinder H will be lowered. Lowering of the cylinder H will force the oil out of said cylinder H through the reversible pump P into the reservoir R. In this operation the pump will drive the motor in a reverse direction as a generator. Suitable braking circuits will be placed around the motor armature to govern the retarding effect of the motor and thereby govern the speed at which the cylinder H is lowered. Not only does the flow of oil communicate rotary motion of the motor

115
120
125
130

to a linear motion of the cylinder, or, conversely, not only does it translate a linear motion of the cylinder to a rotary motion of the motor, but the flow of oil translates 5 from a high speed motion of the motor with small torque to a low speed motion of the cylinder with a large force; or, conversely, it translates a low speed motion of the cylinder to a high speed motion of the motor. By 10 reason of this function it is possible to eliminate gear reduction means and arrangements of cables and sheaves. This may be explained by the statement that if the cable pull of the bell hoist is applied directly to any form of 15 winch or similar mechanism, that mechanism must be heavy enough in construction to handle large forces corresponding to the cable pull. If, on the other hand, it is desired to construct a small winch or other 20 mechanism to handle the bells or counter-weight, it is then necessary to interpose a considerable number of sheaves and cables in order to translate the large forces with slow 25 motion of the bell cables to a smaller force with faster motion at the winch.

The electrical control will now be briefly referred to, said electrical control being unclaimed in this application inasmuch as it forms part of the subject matter of the 30 pending application above identified filed by the present applicant. In order to set the dynamo-electric machine T in operation to drive the pump P to force oil or other liquid into the cylinder H, the start button 37 is depressed 35 momentarily. This closes the circuit from the positive lead 18 through the operating coils 34 and 35 of contactors 20 and 24, respectively, and through the time delay relays 33-33 to the negative lead 18. By 40 reason of the energization of the coils 34 and 35, the contactors 20 and 24 are closed, connecting the dynamo-electric machine T across the leads 18-18 as a motor, having the sections 21, 22 and 23 of the accelerating 45 resistance in series with the armature and series field of said motor. The closing of contactor 20 results in the closing of the auxiliary contact 41, which auxiliary contact is in parallel relationship with the start button 37. Said auxiliary contact 41 therefore provides a maintaining circuit after the operator has released the start button 37. At 50 this time the circuit of the controlling coil 39 of contactor 30 is energized, causing said contactor 30 to open. Circuit is also completed at this time from the positive lead 18 through the stalling limit switch T², through the operating coil 43 of contactor 31, through the auxiliary contact 44 and auxiliary contact 41, to the negative lead 18. The energization of the operating coil 43 causes the 55 opening of contactor 31. At this time the stalling limit switch T² is closed and the slow-down limit switch T³ is open. As a 60 result of the actions recited above, the dynamo-

electric machine T is energized as a motor to drive the pump P. At this time the sections 21, 22 and 23 of the accelerating resistance are in series with the armature 15, and the armature shunting circuits controlled by 70 the contactors 30 and 31 are open. Simultaneously with the above actions, a circuit is completed through the accelerating relay 45, which results in the successive energization 75 of the coils 46^a, 47^a and 48^a, which coils control the accelerating contactors 27, 28 and 29, respectively. Said accelerating relay 45 will be chosen of the time element type, which is well known to those skilled in the art. The successive energizations of the operating coils 46^a, 47^a and 48^a will cause the 80 successive closing of said accelerating contactors 27, 28 and 29, whereby the dynamo-electric machine T will be connected across the leads 18-18 with no sections of accelerating resistance in circuit. The dynamo-electric machine T proceeds to drive the 85 pump P to deliver fluid to the cylinder H to raise same, and the bell A opens by gravity.

When the cylinder H has traveled a short distance, the slow-down limit switch T³ will be moved to closed position; any preferred means responsive to movement of said counterweight being suitable for operating 90 said switch T³. There is no immediate effect from this closure. When the bell A reaches a substantially full open position, the stalling limit switch T² will be opened. Opening of said stalling limit switch T² results in the deenergization of the operating coil 43 of contactor 31, causing said contactor 31 to close. Closure of contactor 31 results in the closure of the auxiliary contactor 50, resulting in the energization of 95 the time delay relay coil 49, which coil 49 controls the time delay relay 33. Opening of said stalling limit switch T² also results in the deenergization of the operating coils 46^a, 47^a and 48^a, whereby the accelerating 100 contactors 27, 28 and 29 are caused to open. At this time the dynamo-electric machine T is connected across the line with all of the sections 21, 22 and 23 of the accelerating resistance in circuit and with the braking resistors 32 shunted across said dynamo-electric machine and sections 21 and 22 of the accelerating resistance. The values of these resistors can be so adjusted that the dynamo-electric machine will practically stall, developing only sufficient torque to hold up the cylinder H. If there should be any movement, the speed of travel would be exceedingly slow. At this time the burden is being 115 permitted to drop from the bell into the blast furnace. Attention is directed at this point to the relief valve R², which permits the dynamo-electric machine T and the pump P to operate in a pumping sense to maintain a pressure to hold up the cylinder H 120 125 130

and to hold the bell A in open position. It may be desired to utilize the functions of the relief valve R² rather than to cause the stalling of the dynamo-electric machine T to give 5 a time delay for dumping. Moreover, the relief valve permits holding the bell open for inspection or cleaning.

After the lapse of a predetermined time, the time delay relay coil 49 will result in the 10 opening of the time delay relay 33, resulting in the deenergization of the coil 34 of contactor 20 and the coil 35 of the contactor 24. The dynamo-electric machine T is now disconnected from the mains, and the weight of 15 the cylinder H will cause the backflow of fluid through the pipe J, pipe P¹ and pump P to the reservoir R. Reverse operation of the pump P will cause the dynamo-electric machine T to operate as a generator with a 20 dynamic braking circuit across the armature and series field, which dynamic braking circuit includes the resistors 21, 22 and 32. The corresponding bell A will close as the cylinder H descends. When near the lower- 25 most position of the cylinder H, the slow-down limit switch T³ will be opened, which open-circuits the coil 39 of the contactor 30, resulting in the closing of said contactor 30, applying a lower resistance dynamic braking 30 circuit across the armature and series field winding of the dynamo-electric machine, bringing the cylinder H and bell A to a safe stop.

The present invention presents many advantages over systems involving winches, cranks, screws and the like as a means for translating the rotary movement of the motor to a desired linear motion. The efficiency of translation of motive power to the bell cables 35 is very high, an advantage which is particularly important in a retroactive control scheme wherein the dynamo-electric machine operates with both motor and generator functions. The present invention also 40 has the advantage that it allows interlocking the electric control with other movements in charging the furnace. It affords independent control of speed in opening and closing the bells through proper control of the motor. 45 As neither of the dynamo-electric machines is provided with a brake, the bells are biased to close; yet they can be held open if desired. This latter function is accomplished by 50 means of the switch X in each of the stalling limit switch circuits, whereby the corresponding stalling limit switch T² or U² may be rendered inoperative. The corresponding relief valve R² or S² then permits short-circuiting of the oil or other liquid through the 55 corresponding pump and reservoir, maintaining a pressure sufficient to hold up the corresponding cylinder H or K. When the switch X in either the line T⁴ or U⁴ is again closed, the cycle is continued and completed; 60 that is, after the time relay functions, the

corresponding cylinder drops, retarded by the pump and the motor, which motor operates as a generator.

The device requires a minimum of floor space, because of the vertical position of the cylinders H and K, and will permit the location of the combination motor pump unit at any point near these cylinders, but without requiring any particular mechanical space relationship. The present invention renders 70 easy a feature which is not attributable to any other electric bell hoist, insofar as applicant is informed, in that the unit comprising a motor pump and its control can be applied either to the large bell or the small bell of a furnace. The operating means for the two bells may be duplicates throughout, the only difference being that the large bell will operate with a higher oil pressure and a heavier counterweight. The simple arrangement of the interconnected piping with valves will allow either pump unit to function in connection with either cylinder, so that repairs can be made upon one unit while the other functions to handle both the large 75 and the small bells. If the pump Q is out of commission, valve Q³ is closed and valve O¹ is opened. In order that the pump unit P may operate on the cylinder K, valve J¹ is closed and valve M¹ is opened. To control 80 cylinder H from the pump unit P, it is necessary to close valve M¹ and open valve J¹. 85

When pump unit P is out of commission, valve P³ is closed and valve O¹ is opened. To control the cylinder H from pump unit 90 Q, valve M¹ is closed and valve J¹ is opened. To control cylinder K from the pump Q, valve J¹ is closed and valve M¹ is opened. 95

By the arrangement of interconnected piping, the advantage is had that either pump unit may function in connection with either cylinder, so that repairs can be made upon one unit while the other functions to handle both the large and the small bells. Moreover, the equipment can be constructed 100 at a cost lower than other comparable types of bell hoist. 105

Though a preferred embodiment of the present invention has been described in detail, many modifications will occur to those skilled in the art. It is intended to cover all such modifications that fall within the scope 110 of the appended claims.

What is claimed is—

1. In combination, a member the movement 115 of which is to be controlled, a counterweight for biasing same to a raised position, hydraulic means for lifting said counterweight to permit said member to descend, and a reversible pump for pumping liquid to said hydraulic means and to receive power from said hydraulic means.

2. In combination, a member the movement 120 of which is to be controlled, a counterweight for biasing same to a raised position,

hydraulic means for lifting said counter-weight to permit said member to descend, a reversible pump for pumping liquid to said hydraulic means and to receive power from 5 said hydraulic means, and a dynamo-electric machine mechanically connected to said reversible pump, said dynamo-electric machine being provided with a braking electric circuit operative to perform braking functions 10 when said dynamo-electric machine is being driven as a motor.

3. In combination, a member the movement of which is to be controlled, a counter-weight for biasing same to a raised position, 15 hydraulic means for lifting said counter-weight to permit said member to descend, said hydraulic means including a reversible pump, a reservoir for fluid, and by-pass means between said reservoir and pump 20 whereby the pressure upon said hydraulic means may be maintained at a desired figure without stopping said pump.

4. In combination, a member the movement of which is to be controlled, hydraulic 25 cylinder means for biasing same to a raised position, a pump for delivering fluid to said cylinder means to permit said member to descend, said pump being reversible, and a dynamo-electric machine electrically connected 30 to said pump whereby to receive energy from said pump for braking purposes.

5. In combination, a member the movement of which is to be controlled, hydraulic cylinder means for biasing same to a raised 35 position, a pump for delivering fluid to said cylinder means to permit said member to descend, said pump being reversible, and a dynamo-electric machine electrically connected to said pump whereby to receive energy 40 from said pump for braking purposes, said cylinder means being vertically disposed whereby to occupy a minimum of floor space.

6. In combination, a member the movement of which is to be controlled, counter-45 weighted cylinder means for biasing same to a raised position, a pump connected with said counterweighted cylinder means for delivering fluid thereto to lift said counterweighted cylinder means to permit said member to descend, a pump for delivering fluid to said cylinder means and for receiving energy from 50 said cylinder means when said cylinder means descends, a dynamo-electric machine connected to said pump, and limit switches 55 adapted to be operated in response to movement of said cylinder means for controlling said dynamo-electric machine.

Signed at Chicago, Illinois, this 24th day
of May, 1927.

60 GORDON FOX.
